ASSIGNORS TO GOOD INVENTIONS CO., OF NEW YORK, N. Y., A CORPORATION OF
NEW YORK

OIL BURNER

Application filed July 8, 1925. Serial No. 42,145.

The invention relates to oil burners of the type intended for house heating purposes, although useful elsewhere, and its object is to provide a safe automatic control system for such apparatus whereby, among other things, it is made impossible for the combustible and an igniting temperature to coexist in the combustion space of the furnace, except according to the proper sequence or during normal combustion, and whereby, especially, the resumption of the burner-operating current, after an interruption caused by thermostat control or otherwise, cannot produce delivery of fuel or the operation of the ignition means until after the lapse of a period of time, say ten minutes or so, sufficient to allow the cooling of all internal parts of the furnace to below ignition temperature. The invention involves various features of control, looking toward the avoidance of accident and dangerous conditions, all of which will be made apparent in the following description, and many of which will be recognized as capable of application with advantage to existing control systems of other types.

In the accompanying drawing Figure 1 is a general diagram of the preferred form of the new system, Figure 2 being a detail elevation of the timing device or servo-motor, and Figure 3 a diagram of the control cycle.

The burner proper with which this invention is adapted for use may be of any desired type and is diagrammatically represented in the drawings as comprising a fan blower 1 and a fuel spray nozzle 2 within a suitable housing, the fan being driven by an electric motor 3. An igniter for the burner is indicated at 4, being in this case an electric resistance or hot wire igniter, which becomes incandescent when energized, although any suitable means of ignition can be easily brought within the control of the present system by suitable adaptation. As a means of avoiding oil leakage when the burner motor is not energized, an oil valve is ordinarily applied to the oil line to the burner, arranged to close whenever the burner motor stops running. Such an oil valve is controlled by the electro-

magnet 5 in the present case bridged across the burner motor leads.

The system is governed primarily by a room thermostat and secondarily by a timing device the function of which is to establish or 55 prepare and also to complete and break the interrelated control circuits below described. The thermostat has no immediate control of the burner except when the latter is operating and then only to stop it and has no control over the timing device except to start it in action. This timing device starts the burner motor and then shifts the control of the latter over to the thermostat, and forbids resumption of burner operation until after 60 the cooling period has intervened. The room thermostat in the present case is an ordinary bi-metallic strip adapted to flex to the right as it cools and make a double contact on such movement, one contact (22) being made directly by the end of the bi-metallic arm itself and the other (28) by means of a flexible finger secured to and moving with it; the design will be clear from the diagram. The double contact is preferred but a single 75 contact thermostat could be made to suffice as later explained. Instead of a thermostat located in the room or space where the temperature is to be controlled, the present system could also be controlled by variation of 80 pressure as by means of a so-called pressurestat adapted to respond either directly or indirectly to changes of boiler pressure. For convenience in this description and in the claims all such heat or pressure-sensitive devices are included in the term "room thermo- 85 stat".

The timing device above referred to can be represented by any slow-moving member capable of being set in action by a circuit completed by the effect of the room thermostat when the latter cools to or below the temperature for which it has been set, and requiring a time interval, after being set in action, before it functions to start or permit the starting of the burner motor. Within the category of devices suitable for this purpose are included motors, thermostatic elements and dash pots when suitably controlled and regulated. Preferably the timing device is con-

stituted of a member having a fixed cycle and so organized that when once started, its full cycle must be carried out before it can repeat any function. A part of such cycle is allotted to the energization of the burner-operating motor and its igniter and appurtenant parts, and the rest, and greater part, is merely time consuming. By this division of the cycle, two successive motor energizations cannot occur without a time interval between them which is made long enough to allow all heated parts in the furnace to cool down to below an igniting temperature, thereby precluding the possibility of an explosion on the resumption of the action of the igniter or of the fuel delivery. The delay thus involved and which may be ten minutes or more, is found to be unobjectionable in an automatic system and represents a positive assurance of safety. In the present case, the timing device is a small motor, herein called and marked the servo-motor. It is geared through appropriate reduction gearing to impart a slow drive to a commutator 6 and two adjacent cams 7 and 8, at the rate of about one revolution in ten or twelve minutes. These parts are shown in elevation in Fig. 2 and their respective developments appear in the diagram of Fig. 1 as a matter of convenience in observing the sequence of operations.

The function of the commutator is to control its own armature circuit and the igniter circuit. The function of the cam 7 is to lift or move the switch armature 9 of the holding magnet 10 so as to close the circuit gap at contact point 11. When this armature has so been moved, the field of the magnet 10 retains it closed, (provided the magnet circuit is not opened elsewhere) independently of further control by said cam. When the holding armature is released it falls, by gravity in the present case, and closes the circuit gap at contact point 32.

The cam 8 is for the purpose of depressing a plunger or striker 12 against a spring and releasing it so as to cause it to strike the switch armature 13 and knock it into its circuit-closing position in which it, like the armature 9, is then held by the field of the magnet 14. In its normal or dropped position, armature 13 is out of the magnet field and cannot be closed by the effect of the magnet alone. The magnet 14 is herein referred to as the motor switch magnet, inasmuch as the closure, by its armature 13, of the gaps at contact points 15 completes the motor-operating circuit 16. This circuit, it will be seen, is connected directly to the main supply leads 17 of the house circuit and may be assumed to carry the usual 110 volt current. Inasmuch as the function of the cams 7 and 8 is merely to cause their respective armatures to be placed in circuit-closing po-

sitions it will be apparent that these cams might readily be substituted by other forms of gap-closing mechanism adapted either to close the gaps at the proper time or to restrain their closing until such proper time.

The servo-motor in the present case is a so-called repulsion motor having its field permanently connected by wires 19 to the supply leads 17. A conducting connection is required to be established between the terminals 20 of its armature winding in order to set it in action, and this armature circuit is thus the controlling circuit for the servo motor.

The high potential or house current is also used for igniting the burner when hot wire ignition is employed and the ignition circuit in the present case is marked 21 being connected to leads 19.

Assuming that the system is out of action, commutator 6 occupies the position, with respect to its several brushes, which is indicated in Figure 1. The three conducting strips 23, 24 and 25 of the commutator are all connected together, as indicated by dotted lines, and two of them, 23 and 24, are engaged with their respective brushes whereby a circuit will be seen to be established which includes the servomotor armature winding, wires 26 and 27 and the room thermostat. By the action of the latter the circuit may be completed, thus starting the servomotor. At such time the two armatures 9 and 13 will be down or farthest removed from their respective magnets and the armature 13 will be out of the field of motor switch magnet 14. When the cooling room thermostat closes against contact 22, it starts the commutator in rotation. The short arm of the thermostat closes the gap at its contact 28 slightly before or coincidently with the closure of gap at 22 and its effect is to establish, but not to complete, a circuit which includes the secondary of the transformer, the two magnets above referred to, the gap (open) at 11, armature 9 and wire 27 back to the thermostat. This circuit is referred to as a holding circuit, since its principal function is to hold both armatures in circuit-closing positions, but it is open, or uncompleted, when the commutator starts to rotate. This circuit is shown by the heavy line in the diagram.

The first effect of the rotating commutator is to bring the commutator strip 30 into contact with the two adjacent brushes of the igniter circuit 21 and thus close the igniter circuit; this may occur in about fifteen seconds after the servo-motor has started; no other action results from this circuit closure, but the igniter, if a resistance element, begins to get hot. Before the igniter strip 30 has passed from under its brushes, the cam 7 will have revolved to such an extent as to lift its armature and thereby close the gap at 11 and thus complete the holding circuit above re-

ferred to; which circuit will continue closed for as long as the room thermostat maintains its contact at 28. The cam 8 will also have depressed the plunger 12 and shortly after the closure of the holding circuit by cam 7, will have released the plunger so as to cause it to strike the motor switch armature 13 and close the motor circuit already referred to. When thus thrown into circuit-closing position the motor switch armature is put into the field of its magnet as already explained and is thereafter retained in such position independently of any further operation of the cam 8 or the commutator. That is to say, the servo-motor has started the burner motor and completed the holding and motor circuits and at the same time has relinquished all further control of those parts, shifting such control to the holding circuit, that is to say, to the room thermostat. If the latter should open the gap 28, both armatures would drop and the burner would stop. Some 125 seconds have been consumed in the rotation of the commutator necessary to start the burner-operating motor and during that period the igniter 4 will have attained an igniting temperature so that on the delivery of fuel ignition occurs, followed by normal combustion. The commutator strip 30 is preferably long enough so that it does not run out from under its brushes for some seconds after the burner motor has started, in order to make ignition certain.

Thereafter when the commutator strip 24 has moved out of contact with its brush, the motor armature circuit above referred to is interrupted and the servo-motor stops. It remains stopped for so long as the holding circuit is active or the burner motor is running, but in its stopped position commutator strip 25 has established contact with the brush of wire 31, the opposite end of which is connected to the lower contact 32 of the holding armature 9. The gap at 32 is open and cannot be closed while the holding circuit and burner motor are active.

If now the room thermostat, on warming, opens the gap at 28, it will thereby interrupt the holding circuit, de-energizing magnets 10 and 14, and releasing both of their armatures, which discontinues the burner operating current. Release of the holding armature 9 closes the gap at 32 and thereby completes a servo-motor armature circuit through wire 31, strips 25 and 23 connected back through wire 27 to the armature 9. This causes the servo-motor to resume operation and complete the rotation cycle of the commutator, rotating it until the brush of wire 31 runs off the end of strip 25 which is the normal or stationary position, indicated in the diagram. The time consumed in such continued or second rotation is approximately ten minutes and during that period the room thermostat is entirely out of control of the burner as well

as of the servo-motor; closure by it of the gap at 22 can have no effect because the commutator brush at the other end of wire 26 is on the dead part of the commutator; closure of the gap at 28 can also have no effect because the holding circuit is broken by the gap at 11 and, as already described, that gap cannot be closed until the armature 9 is lifted by the cam 7 and even if the gap at 11 should be closed in some abnormal way, the burner motor could not be started without the assistance of cam 8 and its spring plunger. Thus after every period of burner action, or conversely, before any second igniter action, there must intervene a cooling period long enough to forestall fuel delivery into a furnace chamber hot enough to ignite it; once the burner has started it can be stopped on the call of the room thermostat but it cannot be restarted until the next stroke of the switch closing plunger. The purpose in closing the switch by hammer stroke is to prevent any possibility of the servo-motor stopping in a switch-closing position and thus holding the switch closed.

Any momentary cessation of the main current supply has the same effect as opening of gap 28 by the thermostat, since the de-energizing of the transformer de-energizes the magnets 10 and 14, their armatures drop and can only be re-closed after the commutator has revolved to such extent as may be necessary to bring the cams 7 and 8 again into action upon them. If the current failure should occur exactly at the moment of the cam closure of the gap at 11, no untoward effect can be produced on resumption, because the motor switch armature 13 has not yet been closed, and a sufficient time interval intervenes between the operation of the two cams in any event to allow the igniter to reach an igniting temperature before the burner comes on. At all other times failure of the current supply results in the opening of gap 11 which cannot be closed until the servo-motor has performed the cooling period part of its cycle, represented by the length of commutator strip 25.

The sequence of the several operations is illustrated in the cycle diagram of Fig. 3 wherein it will be seen that the resistance igniter is energized shortly after the timing device or servo-motor starts rotation, and that some 110 seconds elapse before the burner motor is set in action. This interval is to allow the resistance igniter to attain an igniting temperature before the fuel strikes it and has been found practically necessary for satisfactory and reliable results. The ignition period overlaps the time of closure of the burner switch merely for insurance against failure and although the servo-motor continues in rotation for some seconds after the ignition is off, it could if desired be made to stop coincidently with it. The

time period indicated from the "servo stop" position to the "start" position may be, as stated, about ten minutes to serve as a cooling period for the interior of furnace parts. Inasmuch as the commutator mechanism rotates only in one direction it will be apparent that the igniter heating period must always intervene between each igniter and motor energization and the cooling period between both. The interval between the closing of the holding circuit and of the burner switch is to prevent the possibility of interference with the intended sequence in the event that the current supply should cease just at the moment of closing of gap 11 by cam 8, as already explained.

It will be seen that while the system as above described uses a double-contact thermostat, the two contacts 28 and 22 could, if desired, be consolidated into one.

The switch device diagrammatically indicated at 33 will be understood to be the usual trip switch adapted to operate in the case of leakage of oil, for the purpose of opening the main current supply circuit until re-set by hand.

We claim:—

1. A burner control system comprising a burner motor, a timing device adapted to start the same, a room thermostat adapted to start said timing device, and means enabling the thermostat to stop said motor independently of the timing device.

2. A burner control system comprising a burner motor, a timing device adapted to start the same; a room thermostat adapted to start said device and stop said motor independently of the timing device, and interrelated connections between said thermostat and timing device whereby the latter interposes a cooling period between successive motor startings.

3. A burner control system comprising a burner motor, a timing device adapted to close the switch thereof, a room thermostat adapted to start said device in action and a circuit whereby the thermostat holds said switch closed.

4. A burner control system comprising a burner motor, a motor switch therefor, a holding circuit and magnetic means energized thereby adapted to hold said switch closed but incapable of closing it, a timing device adapted for closing said switch and a room thermostat for starting said timing device and controlling said circuit.

5. A burner control system comprising a burner motor, a motor switch therefor, a holding circuit and magnetic means energized thereby adapted to hold said switch closed, but incapable of closing it, a timing device arranged to close said switch but incapable of holding it closed and of opening it, and a room thermostat in control of said circuit and adapted to start said timing device in operation.

6. A burner control system comprising a motor switch, a striker for closing it, a timing device for actuating said striker, a holding circuit and magnetic means energized thereby adapted to hold said switch closed but incapable of closing it, and a room thermostat in control of said circuit, and adapted to start said device.

7. In a burner control system, a burner-operating motor, igniter and a room thermostat normally out of immediate control of said motor, in combination with mechanism started by the thermostatic action, adapted to energize the igniter and motor, and having means interposing a cooling interval between successive igniter energizations, and means whereby control of the burner-motor, when started, is transferred from said mechanism to the room thermostat.

8. A burner control system comprising the combination with a burner-operating motor, an igniter and a room thermostat normally out of immediate control of said motor, of mechanism normally controlled by the thermostat, arranged to energize first the igniter and then the motor and interpose a cooling interval between successive energizations of said igniter, and a holding circuit, including the thermostat, established by the action of said mechanism.

9. In an electric burner control system, a burner motor and an operating circuit therefor, an electromagnetic motor switch for said circuit, a room thermostat adapted to close a gap in the motor switch circuit and a timing device also controlling a gap in said motor switch circuit.

10. In an electric burner control system, the combination with the burner-operating motor, of an electromagnet to control the circuit of said motor, a room thermostat, a timing device, and means controlled by said timing device for establishing a holding circuit which includes said magnet and thermostat, whereby the latter is in direct control of said magnet.

11. In an electric burner control system, a burner motor, an electromagnet to control the same, a room thermostat controlling a gap in the magnet's circuit, a timing device also controlling a gap in said circuit, and a circuit for starting said timing device in action having a gap also controlled by said thermostat.

12. In an electric burner control system, a burner motor, an electromagnet to control the same, a room thermostat controlling a gap in the magnet's circuit, a timing device also controlling a gap in said circuit, a circuit for starting said timing device in action having a gap also controlled by said thermostat, and means whereby failure of said

magnet's circuit also starts said timing device.

13. In a burner control system, a burner motor, a motor switch therefor, a room thermostat, a timing device set in motion by the action of said thermostat and adapted to close said switch and stop its own motion, independently of said thermostat, while the burner motor is energized, and means whereby said timing device continues its motion 10 when the burner motor is deenergized.

14. In a burner control system, a burner motor and igniter, a holding circuit for the burner motor, a servomotor adapted to energize said igniter and burner motor, establish said holding circuit and then stop its own motion, and means controlled by said holding circuit for causing continued operation of said servomotor when said holding 20 circuit is broken.

15. In a burner control system, a circuit including two magnets, the armature for one of said magnets being adapted to close said circuit, a device to move said armature to circuit closing position, a burner motor circuit controlled by the armature of the other magnet and means for causing the latter armature to close the burner motor circuit after said magnet circuit has been closed.

16. In a burner control system, a room thermostat, a circuit containing a gap controlled by said thermostat and also containing a holding magnet and a gap adapted to be held closed by said magnet, electromotor means adapted for closing said last mentioned gap but incapable of opening it, and means whereby the room thermostat sets said means in action.

17. In a burner control system, a room thermostat, a circuit containing a gap controlled by said thermostat and another gap, slow moving means started by the room thermostat and adapted for closing said last mentioned gap, a holding magnet in said 45 circuit adapted for holding said gap closed but incapable of closing it independently of said means, and a burner-operating motor held energized by said circuit.

18. A burner control system, a burner 50 motor, an electromagnet to control the same, a double-contact room thermostat, a timing device started in action by a circuit through one of said contacts and a holding circuit including the other thermostat contact and 55 established by the action of said timing device.

19. In a burner control system, a burner 60 motor, and a double contact room thermostat normally out of direct control of said motor, in combination with an electrically operated timing device having a circuit including one of said thermostat contacts whereby it is started, a holding circuit including the other 65 of said contacts, a magnet in said holding

circuit and means whereby said magnet controls the operating current to said motor.

20. In a burner control system, a burner motor, a resistance igniter and a room thermostat, in combination with a servo-motor, 70 and means operated thereby for successively causing energization of the igniter and motor, said means including a magnet, an armature therefor and means driven by the servo-motor for operating said armature.

21. In a burner control system, a burner-operating motor and a resistance igniter, a magnet to control the motor, a room thermostat adapted to close a gap in the circuit of said magnet and a timing device adapted to 80 close the igniter circuit and also controlling a gap in said magnet circuit.

22. In a burner control system, the combination with a burner motor circuit and an igniter, of a room thermostat circuit, a timing device started in response to closure of the room thermostat circuit, connections whereby the igniter, and, after an interval, the burner circuit are energized by the timing device, said timing device being adapted 90 subsequently to cause de-energization of the igniter and means whereby opening of the thermostat circuit stops the motor.

23. In a burner control system, the combination of a room thermostat circuit and a timing device, means whereby the room thermostat starts the burner through said timing device and means whereby opening of the room thermostat circuit stops the burner independently of the timing device.

24. In a burner control system a room thermostat circuit, a burner motor started in response to closure of said circuit and stopped in response to opening thereof, an igniter energized in response to closure of the room thermostat circuit, means for interposing a delay between the energization of the igniter and starting of the burner motor and means for de-energizing the igniter independently of the room thermostat circuit.

25. In a burner control system, a room thermostat circuit, a burner motor started in response to closure of said circuit and stopped in response to opening thereof, an igniter and means for interposing a delay between successive motor energizations.

In testimony whereof, we have signed this specification.
